UNITED STATES PATENT OFFICE

LELAND J. VOLQUARDSEN, OF SAN FRANCISCO, CALIFORNIA

SPRING HINGE FOR ICE-BOX DOORS

Application filed April 10, 1928. Serial No. 268,826.

This invention resides in the provision of an improved hinge for ice box and refrigerator doors, the hinge being constructed to serve as a spring closing means for the door and as a means for locking the door in an air tight closed position, thereby making the hinge serve a triple purpose and doing away with the necessity of using three separate and distinct devices, to wit: a hinge, a spring closing device, and a latch.

One of the objects of the invention is to provide a compact, strong, durable and efficient hinge of the character described which, when the door to which it is attached is moved from open to nearly closed position, will forcibly swing the door from the nearly closed position into fully closed position, and hold the door in such closed position under sufficiently heavy spring pressure to insure the maintaining of an air tight seal without the use of separate pressure latch.

Another object of the invention is to provide a spring hinge of the character described which is provided with a novel means for controlling the action of the spring in the operation of the door with which the hinge is associated.

The main objection to ice box and refrigerator doors such as now generally employed is that some manually operated latch must be manipulated to fasten the door in closed position and make a tight seal of the refrigerator or ice box. It frequently happens that these manually operated latches are either improperly manipulated or fail and prevent a proper sealing or a proper holding of the door in closed position. These failures bring about waste of ice and of food, and are serious objections particularly in large cafes and restaurants where extensive and proper refrigeration is necessary. Furthermore in large ice boxes and refrigerators the doors, in order to provide proper thermal insulation, are necessarily heavy and a great deal of effort is required to open and close such doors.

The present invention provides in a single hinge unit, for the automatic movement of the door into closed position following a pre-determined closing movement of the door,

for forcibly closing the door and forming a tight seal by spring action, and for holding the door thus closed under the strong spring tension and preventing accidental dislodgement of the door from its air tight closed position. Thus, it may be said that the device of my invention provides for an automatic closing and fastening of the door thereby overcoming the objections attending the use of doors having manually operated fastening devices. Among the advantages of the spring hinge of this invention is the provision for counterbalancing the door whereby it may be easily operated and will be maintained in open position and may be used as a shelf or tray in the operation of putting food and other articles into or removing food or other articles from the ice box or refrigerator.

Another purpose of the invention is to provide a hinge of the character described which may be used without change in the construction thereof in connection with doors which swing either upward into open position or downward into open position, a change of location only being necessary with regard to the installation of the hinge to make it operate on a downwardly opening door instead of an upwardly opening door and vice versa.

With the above mentioned and other objects in view, the invention consists in the novel construction and combination of parts hereinafter described, illustrated in the accompanying drawings and set forth in the claims hereto appended, it being understood that various changes in the form, proportion, size and minor details of construction within the scope of the claims may be resorted to without departing from the spirit or sacrificing any of the advantages of the invention.

Referring to the drawings:

Fig. 1 represents a front elevation of the hinge of my invention as it would appear when applied to a door of an ice box or refrigerator, the parts being in position with the door closed, part of the door being shown.

Fig. 2 represents a vertical sectional view taken on the plane of line 2—2 of Fig. 1.

Fig. 3 represents a vertical sectional view taken on the same plane as Fig. 2 but showing

the hinge as it would appear when the door is open, part of the door being shown.

Fig. 4 represents a cross sectional view taken on the plane of line 4—4 of Fig. 1.

5 Fig. 5 represents a fragmentary front elevation of an ice box showing the hinges and door with the latter in closed position.

Fig. 6 represents a vertical sectional view of the hinge as it would appear when used 10 with a door adapted to swing down into closed position instead of up.

Fig. 7 represents a vertical sectional view of the hinge arranged as shown in Fig. 6 but with the parts in position assumed when the 15 door is open.

Fig. 8 represents a horizontal sectional view taken on the plane of line 8—8 of Fig. 7.

Fig. 9 is a fragmentary front elevation of 20 a refrigerator showing the hinges arranged to operate when the door is swung upward into closed position instead of downward as shown in Fig. 5.

The embodiment of the invention which is shown in the accompanying drawings comprises a hinge casing generally designated 1 and which is adapted to be secured by screws 2 to an ice box or refrigerator designated A, there being a suitable bearing 3 for the horizontal pintle or trunnion 4 of the ice box 30 door B, which door in this instance is mounted so that it swings downward from closed into open position.

The pintle or trunnion 4 has a pinion 5 keyed thereon, which pinion meshes with the 35 teeth 6 of a rack bar 7 which bar is vertically reciprocally mounted in the casing 1. The rack bar 7 has an expansion spring 8 mounted thereon with the lower end of the spring resting upon a shoulder 9 and the upper end 40 of the spring bearing against the under side of a guide block 10 removably held in the casing by screws 11. The upper portion of the rack bar slides through an opening 12 provided in said block. By this arrangement 45 with the door hung as shown in Fig. 5, with two hinges of my invention, one at each end, when the door is swung downward from closed into open position, the pinions 5 engaging the teeth 6 of the rack bars 7 cause 50 said rack bars to move upward and compress the springs 8. These springs operate as will be later more fully described, to effect the closing of the door and a holding of the door in closed position so as to form an air tight 55 seal. The door is counterbalanced by the springs 8 and the closing force of the springs does not become effective until the door has been moved into a position near the vertical. Thus the door will remain at any point between a predetermined nearly closed position and a fully open position and being 60 counterbalanced can be operated easily.

I provide a means which will assist in counterbalancing the door and also bring 65 about a forceful quick closing movement and

a securing of the door in closed position against unintentional opening movement. This means is adjusted so that it may be regulated to suit the conditions at hand and to vary the closing and locking operations 70 as desired. This means is in the nature of a spring urged detent, which may be ar-

anged to set up sufficient friction to assist in counterbalancing the force of the door. This spring urged detent means in being urged into detenting position brings about a quick, forceful closing of the door and then serves as a forceful and strong yielding latch which holds the door against being moved out of properly closed position unintentionally but will readily yield when the door is 75 grasped and pulled open. In detail this

means in the present embodiment comprises a pivoted member generally designated 13 carrying a detent member 14 in the form of a roller, which roller rides upon one side of the rack bar 7. A spring 15 urges this member and roller into engagement with the rack bar. A depression or notch 16 is provided in the rack bar for reception of the roller 14.

80 The member 13 comprises an inverted L-shaped piece 17 pivoted between its ends as at 18 within the casing 1. Attached to one side of the vertical leg of the piece 17 is an elongated plate 19 secured in place by means of a screw 20 which passes through an elongated slot 21 in the plate and into the piece 17.

85 On the upper end of the plate 19 is a lateral projection 22 which is engaged by the lower end of an adjusting screw 23 carried by the piece 17. The plate 19 is provided with flanges 24 along its opposite edges and the roller 14 is journaled between these flanges. Rods 25 carried by the casing 1 extend on opposite sides of the rack bar 105 through enlarged openings 26 in the lower end of the plate 19 and are provided with screw threaded outer terminals upon which nuts 28 are mounted. The springs 15 are mounted on the rods 25 between the nuts 28 and the outer side of the plate 19 and force the plate towards the rack bar so as to yieldingly hold the roller in engagement with 110 said rack bar. The tension of these springs may be regulated by the nut 28. The plate 115 19 may be vertically adjusted by loosening the screw 20 and manipulating the screw 23, the enlarged openings 21 and 26 permitting movement of the plate relative to the screw 20 and rods 25. By these adjustments the 120 timing of the closing and fastening operations may be varied as desired. To limit the downward movement of the door to the horizontal, a stop member 30 is provided on the casing 1 in position to be engaged by the 125 upper end of the rack bar 7.

With the hinge arranged as shown in Figs. 1 to 5 inclusive, a second depression or notch 31 provided in the member 7 is sealed with suitable material such as Babbitt metal in- 130

dicated at 32 so as to provide a smooth face. This Babbitt metal is removed in the instance of another use of the hinge as will be later more fully described. However, if desired the depressions 31 may be left open as is the depression 16 and in this event the door will be securely held in down or open position.

In the operation of the hinge of my invention arranged as shown in Figs. 1 to 5 inclusive, assuming that the door is closed and the hinge parts are in the position shown in Figs. 1 and 2, when the door is pulled downward, the pinion and rack bar 5 and 7 operate to push the rack bar up and compress the spring 8. Thus the opening of the door is effected against the action of the springs of the two hinges and the heavy doors will be counterbalanced so that they may be easily and effectively opened without slamming. But a slight pull is necessary to start the door, it being necessary to disengage the roller 14 from the notch 16 in the starting operation. The roller 14 being spring urged against the member 7 sets up friction and thereby assists in counterbalancing the door. When the door is to be closed it is swung upward and this movement is assisted by the springs 8 of the hinges. Ice box and refrigerator doors are usually exceptionally heavy and the provision for counterbalancing the doors by the hinges of this invention makes for an easier and better operation of the door than is ordinarily the case. When the door reaches a point near the vertical, on being closed, the force of the spring is greater than the weight of the door and the door is quickly moved by said springs into closing position, the rollers 14 then extending into the notches 16. The springs 15 pressing these rollers 14 against the curved surfaces of the notches 16 provide a cam action which aids the springs 8 in effecting the closing movement, thus giving a quick closing action, inasmuch as this cam action tends to move the rack bar 7 downwardly. With the rollers extending into the notches 16 as shown in Fig. 2, the door is effectively held in closed position under spring pressure and will therefore be secured against unintentional opening movement. This closing pressure may be varied to some extent by adjusting the plate 19 carrying the roller to cause the roller to extend a greater or less extent into the notch as desired. In this way the door is automatically fastened in closed position and the fastening means also assists in the closing movement due to the leverage force imparted by said locking means when the rollers 14 thereof extend into the notches 16.

Referring to Figs. 6 to 9 inclusive, the hinges are arranged to provide for hanging the door from the upper side so that the door is opened by being swung upwardly and closed upon being swung downwardly. This arrangement is usually necessary where the

compartment for which the door is used is disposed above normal shoulder height in ice boxes and refrigerators. The hinges are placed at the upper edge of the door as shown in Fig. 9 and operate in substantially the same manner as previously described. Fig. 6 shows the door in closed position but the hinge parts are at this time in the position which they assume when the door is hung and is in the position as shown in Fig. 3 with the rollers 14 engaged in the lowermost notches 31. In hanging the door the hinges and door are set up so that the springs 8 are under maximum compression when the door is closed (see Fig. 6). To open the door, it is swung upward and the pinions 5 move the rack bar 7 downward. This movement of the rack bars is assisted by the compressed springs 8 and these springs therefore through the rack bars and pinions tend to lift the doors during the opening thereof. In this way the usually heavy doors may be easily lifted due to the assistance given by the springs 8. It is only necessary to exert a quick forceful pull on the door to start the opening movement, this pull being necessary to move the rollers 14 out of the notches 31 which normally function to hold the door in closed position. When the door has been moved into nearly horizontal position, the rollers again engage in the notches 16 and thereby hold and fasten the door in open position and against accidental dislodgment from said position. To close the door it is given a quick forceful pull to disengage the rollers 14 from the notches 16 and the closing movement is effected against the action of the springs 8 which are compressed during such movement. In this way heavy doors may be easily let down into closed position without slamming. The springs 8 assist in holding the door open and assist in closing it also. The rollers 14 riding on the rack bars 7 during the closing movement and being under strong spring pressure assist in counterbalancing the door, and when the door moves to a nearly vertical position, the rollers will snap into the notches 31 and thereby quickly and forcibly move the door into final closed position. The spring force of the rollers acts as a leverage to push the rack bars 7 upward and the fastening means thereby assists in effecting the final closing movement.

The hinge of my invention is particularly advantageous for use in refrigerators and ice boxes of the larger types used in large cafes and restaurants in that it permits of an easier, quicker and more reliable operation of the doors, saves a great deal of time and labor in manipulating the doors, and provides an automatic closing and holding of the doors in closed position whereby proper sealing and refrigeration is insured.

I claim:

1. A hinge of the character described com-

prising a housing, a bar reciprocally supported upon the housing, means associated with the housing and door and adapted for connection with the door, which means when the door with which it is connected is moved into open and closed positions will reciprocate said bar, a spring associated with said housing and bar, which spring acts as a counterbalance for the door, and a spring urged detent means operating to automatically accelerate the closing of the door when the door is in nearly closed position and to hold the door in closed position against unintentional opening movement.

2. A hinge of the character described comprising a casing, means associated with the casing and upon which a door may be hung, which means moves when the door is moved, a member on the casing associated with the door and moved by said means, an expansion spring associated with said member, which spring expands on movement of said member in one direction and is compressed on movement of said member in the other direction and a spring urged means which when the door is nearly closed accelerates the closing thereof and when the door is closed yieldingly holds the movable member in a position to maintain the door closed under spring pressure.

3. A hinge comprising a hinge casing, a hinge pin revolvably connected with the casing and adapted to have a door attached thereto so that the pin will turn when the door is opened and closed, a member movably supported on the casing, means of connection between said member and said pin providing for movement of the member on rotation of the pin, an expansion spring tending to move said member in one direction and which expands on one movement of said member and contracts on the other movement of said member, and means which when the door is near to a predetermined position will engage said movable member so as to accelerate its movement toward said position and to yieldingly hold said member in position to maintain the door in said predetermined position against unintentional movement out of said position.

4. A hinge comprising a casing, a hinge pin revolvably connected with the casing and adapted to have a door fixed thereto, a bar slidably in the casing and having a notch therein, a means of connection between the bar and pin providing for movement of the bar on rotation of the pin, an expansion spring associated with the casing and bar and arranged to expand on movement of the bar in one direction and to be compressed on movement of the bar in the other direction; a detent member engaged with said bar and adapted to extend into said notch on movement of said bar into a predetermined position; and spring means yieldingly holding

said detent in engagement with the bar, said detent member and said notch being adapted to coact for accelerating the movement of said bar when the bar is nearing the said predetermined position.

5. A hinge comprising a casing, a hinge pin revolvably connected with the casing and adapted to have a door fixed thereto, a bar slidably in the casing and having a notch therein, a means of connection between the bar and pin providing for movement of the bar on rotation of the pin, an expansion spring associated with the casing and bar and arranged to expand on movement of the bar in one direction and to be compressed on movement of the bar in the other direction, a member pivotally mounted in the casing, a roller carried by said member and engaging with the bar, which roller is adapted to extend into said notch on movement of the bar to bring the notch opposite the roller; and spring means yieldingly holding said roller in engagement with said bar, so as to cause said roller to accelerate the movement of the bar when the notch is moved toward and into partial engagement with the roller.

6. A hinge comprising a casing, a hinge pin revolvably mounted upon the casing and adapted to have a door attached thereto, a rack bar slidably mounted upon the casing, a pinion carried by said pin and engaging the teeth of the rack bar, said rack bar having a notch therein, a shoulder on said rack bar, a helical expansion spring mounted upon the rack bar with one end engaging said shoulder, a member mounted on the casing and with which the other end of the spring engages, a member pivoted within the casing, a roller carried by said member and contacting with said rack bar, which roller is adapted to extend into the notch of the rack bar; and spring means yieldingly holding said pivoted member in position to maintain the roller in yielding engagement with said rack bar, said member being adjustable to vary the leverage of the roller action upon the bar.

7. A hinge comprising a casing, a hinge pin revolvably mounted upon the casing and adapted to have a door attached thereto, a rack bar slidably mounted upon the casing, a pinion carried by said pin and engaging the teeth of the rack bar, said rack bar having a notch therein, a shoulder on said rack bar, a helical expansion spring mounted upon the rack bar with one end engaging said shoulder, a member mounted on the casing and with which the other end of the spring engages, a member pivoted within the casing, a roller carried by said member and contacting with said rack bar, which roller is adapted to extend into the notch of the rack bar so as to act at times as a movement accelerating mechanism, spring means yieldingly holding said pivoted member in position to maintain the roller in yielding engagement with said rack

bar; and means for adjusting the roller supporting member to vary the position of the roller.

8. In a hinge a hinge casing, a horizontally disposed hinge pin rotatably connected with the casing and adapted to have a door hung thereon, a bar slidably mounted within the casing, an expansion spring associated with the casing and bar, means of connection between the bar and pin providing for movement of the bar on rotation of the pin, the spring compressing on movement of the bar in one direction and expanding on movement of the bar in the other direction and acting to counterbalance the weight of the door attached to the hinge pin and a spring urged detent adapted to yieldingly engage the bar when the bar is in door closing position.

9. In a hinge a hinge casing, a horizontally disposed hinge pin rotatably connected with the casing and adapted to have a door hung thereon, a bar slidably mounted within the casing, an expansion spring associated with the casing and bar, means of connection between the bar and pin providing for movement of the bar on rotation of the pin, the spring compressing on movement of the bar in one direction and expanding on movement of the bar in the other direction and acting to counterbalance the weight of the door attached to the hinge pin and a spring urged detent adapted to yieldingly engage the bar when the bar is in door closing position, said bar and detent having co-acting faces which when engaged cause the bar to be urged in a direction which will maintain the door closed.

10. A hinge comprising a hinge casing, a rack bar slidably mounted upon the casing, a horizontal hinge pin rotatable upon the casing and adapted to have a door connected therewith, a pinion fixed to the hinge pin and engaging the teeth of the rack bar, an expansion spring associated with the casing and rack bar and arranged to compress on movement of the rack bar in one direction and to expand on movement of the rack bar in the other direction, said rack bar having a notch therein, a member pivoted on the casing, a plate adjustably supported on said member, a detent roller carried by the plate and engaging said rack bar, which roller is adapted to extend into the notch on movement of the bar to a predetermined position, and to coast with said notch for accelerating the bar movement near to said position, means providing for adjustment of said plate to vary the position of the roller, and spring means yieldingly holding the roller in engagement with said rack bar.

11. A hinge comprising a hinge casing, a rack bar slidably mounted upon the casing, a hinge pin rotatable upon the casing and adapted to have a door connected therewith, a pinion fixed to the hinge pin and engaging the teeth of the rack bar, an expansion spring

associated with the casing and rack bar and arranged to compress on movement of the rack bar in one direction and to expand on movement of the rack bar in the other direction, said rack bar having a notch therein, a member pivoted on the casing, a plate adjustably supported on said member, a detent roller carried by the plate and engaging said rack bar, which roller is adapted to extend into the notch on movement of the bar to a predetermined position, means providing for adjustment of said plate to vary the position of the roller, spring means yieldingly holding the roller in engagement with said rack bar, said spring means comprising rods fastened to the casing, said plate having openings therein through which the rods loosely extend, adjustable members on the outer terminals of the rods and expansion springs mounted on the rods with their terminals engaged with said plate and said adjustable members.

12. The combination with a door and a mounting therefor, of hinges connecting said door with said mounting, each of said hinges comprising a slide bar, means of connection between the door and said slide member providing for movement of the slide member in one direction on opening of the door and in the other direction on closing of the door, spring means associated with said slide member and against the action of which said slide member moved in one direction and means for yieldingly holding said slide member against movement incident to closing of the door, which means releases the door incident to intentional movement of the door on being opened, and which accelerates the closing movement of the door in a nearly closed position thereof.

13. The combination with a door and a support therefor, of hinges connecting the door with the support, each of which hinges includes a slide bar, means of connection between the door and slide bar providing for movement of the slide bar in one direction on opening of the door and for movement of the slide bar in the other direction on closing of the door, spring means associated with said bar and compressing on one movement and expanding on the other movement of the door, which spring means counterbalances the weight of the door, and means operating automatically when the door is moved into nearly closed position for quickly and forcibly closing the door and maintaining the door in closed position under spring pressure, which means includes a spring urged detent yieldingly engaged with the bar and a portion on the bar with which said detent engages so as to hold the bar against unintentional movement when the door is closed.

14. The combination with a door and a mounting therefor, of hinges connecting the door with the mounting, which hinges in-

clude hinge pins disposed in a horizontal plane whereby the door is movable up and down, each hinge also including a spring means operatively connected with the mounting and the door and which counterbalances the door and assists in maintaining the door closed under spring pressure, which spring means is automatically brought into play upon manipulation of the door, and a spring urged detent means operating to hold the spring means against unintentional movement out of a position maintaining the door closed, and to accelerate the closing movement of the door near to its closed position.
